PACKAGING MACHINE

Stanley R. Howard, Milton, Mass., assignor to
Pneumatic Scale Corporation, Limited, Quincy,
Mass., a corporation of Massachusetts

Application July 28, 1937, Serial No. 156,156

9 Claims. (Cl. 93—36)

This invention relates to a packaging machine and particularly to a bottom sealing machine of the type provided with forming blocks upon which the cartons are supported while the bottom sealing operations are being performed.

One object of the invention is to provide a novel and improved bottom sealing machine of the character specified in which provision is made for punching a hole through the bottom of the 10 carton, and preferably through the closed and sealed bottom flaps of a carton while the latter is supported on the forming block.

Another object of the invention is to provide a novel and improved bottom sealing machine of the character specified in which a punch is provided at one station of operation which is adapted to cooperate with a die carried by each of a plurality of forming blocks arranged to be successively advanced into operative relationship 20 with the punch, and in which provision is made at a succeeding station of operation for stripping the carton from the forming block and for thereafter clearing the punched out portion from the die.

With these objects in view and such others as may hereinafter appear, the invention consists in the bottom sealing machine and in the various structures, arrangements and combinations of parts hereinafter described and particularly defined in the claims at the end of this specification.

In the drawings illustrating the preferred embodiment of the invention; Fig. 1 is a diagrammatic plan view of a bottle sealing machine embodying the present invention; Fig. 2 is a side elevation of the bottle sealing machine; Fig. 3 is a perspective view of the carton produced by the machine; and Fig. 4 is a cross sectional detail of one of the forming blocks.

The present invention contemplates in its preferred form a bottom sealing machine of the type characterized by having forming blocks on which the cartons are supported while the bottom sealing operations are performed and in 45 which provision is made for punching a hole in the bottom of the carton thus supported on the block and for thereafter removing the punched out sections remaining in the forming blocks after the carton has been removed from the block.

Referring now to the drawings, the different features of the invention are illustrated as embodied in a machine for closing and sealing the bottom flaps of cartons, and except as to such 50 details as are hereinafter pointed out, the illus-

trated machine comprises any of the usual forms of bottom sealing machines now upon the market. Reference is made to the patent to W. S. Scales, No. 767,445, dated August 16, 1904, as disclosing the details of construction and mode of operation of such prior art bottom sealing machines.

As is generally known, and as illustrated in the Scales patent, No. 767,445, above referred to, these prior art bottom sealing machines have included four forming blocks upon each of which a carton is placed by suitable mechanism, with the bottom flaps of the carton projecting below the bottom of the block. Successive cartons are placed upon successive blocks as each block is moved into a definite station, and thereafter a particular block with its carton is intermittently revolved through successive steps of 90 degrees each to permit the different operations of folding and sealing the bottom flaps of the carton to be performed.

Inasmuch as many portions of the bottom sealing machine of themselves constitute no part of the present invention, it has been deemed sufficient to illustrate only sufficient portions of the bottom sealing machine as will enable the present invention to be understood and as herein shown, 20 10 represents the usual rotatable spider upon which four forming blocks 12 are mounted to revolve therewith. The different stations of the machine, as diagrammatically illustrated in Fig. 1, include: station 1, at which the carton is placed upon a block; station 2, at which the bottom flaps are folded and sealed; station 3, at which pressure is applied to the bottom of the carton to firmly set the sealed flaps; and, station 35 4, at which the carton is removed from the block and delivered to an outgoing conveyor 8 to be carried away from the machine.

The spider 10 is arranged to be intermittently rotated by the usual form of Geneva drive including the Geneva wheel 14 and driver 16 through the cooperating gears 18, 20. The driver 16 is rotated from a convenient source of power through a shaft 22 and bevel gears 24, 26, the latter being mounted upon a drive shaft 28.

Referring to Figs. 2 and 4, the mechanism for punching a hole in the bottom of the carton, generally indicated at 32, is located at station 3 where the operation of applying pressure to the bottom of the block to set the previously sealed bottom flaps of the carton is performed. As herein shown, the punching mechanism is formed as a part of and is arranged to operate simultaneously with the usual presser pad. The presser pad comprises the usual vertically recip-

The light-source 10, where of neon tube character, may be actuated by a flashing circuit comprising a secondary winding 33 of a transformer T whose primary winding 34 is supplied by a suitable 5 source of low potential current, for instance a battery 35. The transformer T and battery 35 may conveniently be placed upon the shelf s above the light and tube mounting. In circuit also with the primary winding and the current source is a commutator 36 which may comprise a body of insulation and a commutator bar 37 of copper or other suitable metal, arranged to be contacted by a pair of brushes 38, 39, carried on a brush holder 40. A convenient switch, as a double pole single throw 10 switch 41 serves to control the circuit. The commutator brushes 38, 39 may be of rod-form, of carbon or graphite composition, and with a spring 42 suitably arranged, constant contact with the commutator is assured. The commutator 36 is 15 carried by one of the shafts in the machine, such as to give properly timed contact for the closing of the circuit to produce the light flash upon the rapidly moving impressed paper web. In the form shown, the commutator is mounted on the shaft of 20 one of the cutter rolls 4.

In operation, the web of paper is fed through the series of printing rolls A, B, C, and the impressing or impression surfaces at A, B, C, for example, may apply successive color impressions, 25 as in the three-color process, and the impression surfaces at D, E, may apply black, as printing, etc., the entire assembly then providing colored illustrations and printed text. With the paper web thus subjected to successive impression- 30 applying surfaces, the operator views it in its rapid motion, as he sights through the eye piece 14 of the vising-tube. At the same time, the commutator bar 37 of the commutator on the cutter-roll is making rapid contact with brushes 38, 39, thereby completing the circuit of the primary winding of the transformer, and correspondingly providing impulses in the secondary circuit to the light-tube 10. The voltage here 35 may be of any suitable order, for instance 15,000 volts. If conveniently-located regulating means 40 be close at the hand of the operator, he is thus in a position to regulate the register of the successive impression-applying rolls. For example, a desirable means for this may comprise adjustable slack-rolls 50, 51, between successive impression-applying cylinders. With these, the paper web threads over the rollers 50, 51, such as 45 to provide a variable amount of slack between the successive printing cylinders, and by adjusting the angular position of roller 50 with respect to roller 51, more or less of the slack may be used, and correspondingly the paper web may be advanced or retarded with respect to the succeeding impression-applying surface, and thus 50 the point of application may be brought into accuracy of register. With a swing mounting of roller 50, as for instance on swing-arms 52, and a hand-wheel 53 controlling a screw-threaded stem 54 taking into a nut 55, the angular position of the roller 50 may be simply and accurately 55 controlled.

It is thus unnecessary to wait until the finished product has gone clear through the machine before checking and adjusting the register. Rather, this may be accomplished as the web travels 60 along from the successive impression-applying surface, and irrespective of the speed, immediate and accurate register-adjustment may be made with convenience by the operator.

75 Other modes of applying the principle of the

invention may be employed, change being made as regards the details described, provided however, the features set forth in any of the following claims, or the equivalent of such, be employed.

I therefore particularly point out and distinctly claim as my invention:—

1. In printing machinery having a series of cylinders for applying ink impressions in succession to a travelling web of paper and having 10 means for regulating said travelling web so as to obtain accurate register of said impressions, viewing means for obtaining a standstill view of said web to ascertain the register of the printed impressions, said viewing means including means 15 for flashing light on the web and means in synchronism with the speed of travel of said web for providing the flashes, said viewing means being located in operating reach of said regulator means. 20

2. In printing machinery having a series of cylinders for applying ink impressions in succession to a travelling web of paper and having means for regulating said travelling web so as to obtain accurate register of said impressions, folding and cutting means over which the printed web runs, means for obtaining a standstill view of said web to ascertain the register of the printed impressions and including means for flashing light on the web, and a commutator connected 30 with said folding and cutting means for timing the flashes of light with the travel of the web. 25

3. In printing machinery having a series of cylinders for applying ink impressions in succession to a travelling web of paper and having means 35 for regulating said travelling web so as to obtain accurate register of said impressions, folding and cutting means over which the printed web runs, means for obtaining a standstill view of said web to ascertain the register of the printed impressions, including means for flashing light on 40 the web and means operating in timed relation with said folding and cutting means and having a controlling-connection to said light-flashing means for timing the flashes of light with the travel of the web. 45

4. In printing machinery having spaced apart longitudinally extending framing elements and a series of cylinders transversely mounted therebetween for applying ink impressions in succession to a travelling web of paper and having means for regulating said travelling web so as to obtain accurate register of said impressions, folding and cutting means over which the printed web runs, means for intermittently flashing light on the 50 web, means for timing the flashes of light with the travel of the web, a controlling-connection between said timing means and said light-flashing means, and a viewing tube sighting upon the travelling web between said cylinders and said 55 folding and cutting means.

5. In printing machinery having spaced apart longitudinally extending framing elements and a series of cylinders transversely mounted therebetween for applying ink impressions in succession to a travelling web of paper and having means for regulating said travelling web so as to obtain accurate register of said impressions, folding and cutting means over which the printed web runs, means for intermittently flashing light 60 on the web, means for timing the flashes of light with the travel of the web, a controlling-connection between said timing means and said light-flashing means, and a sighting tube with one end facing the web and the other end extending 65

3. In a bottom sealing machine for sealing the bottom flaps of cartons, in combination, a forming block provided with a die in the bottom thereof, means for operatively supporting said forming block, connections between said supporting means and said block adapted to permit the block to be moved laterally with relation to said supporting means, a punch member adapted for cooperation with the die, means for operating the punch member to punch an opening in the bottom of the carton and to deposit the punched out portions of the bottom of the carton in the die, and means for thereafter clearing the punched out portions of the carton from the die.
4. In a bottom sealing machine for sealing the bottom flaps of cartons, in combination, a forming block provided with a die in the bottom thereof, means for operatively supporting said forming block, connections between said supporting means and said block adapted to permit the block to be moved laterally with relation to said supporting means, a punch member adapted for cooperation with the die, means for operating the punch member to punch an opening in the bottom of the carton and to deposit the punched out portions of the bottom of the carton in the die, and a clearing member supported within the block and movable into the die for removing the punched out portions therefrom.
5. In a bottom sealing machine, in combination, a forming block, means for operatively supporting said forming block, connections between said supporting means and said block adapted to permit the block to be moved laterally with relation to said supporting means, means for sealing the bottom flaps of a carton, including a member for pressing the bottom flaps against the bottom of the block, a die disposed in the bottom of the block, and a punch member adapted to cooperate with the die to form an opening in the bottom of the carton, said punch member being operatively supported by said bottom flap presser member whereby the pressing and punching operations are performed in one operation.
6. In a bottom sealing machine for sealing the bottom flaps of cartons, in combination, a forming block provided with a die in the bottom thereof, means for operatively supporting said forming block, connections between said supporting means and said block adapted to permit the block to be moved laterally with relation to said supporting means, a punch member adapted for cooperation with the die, registering means for effecting alignment of the die and the punch, and means for thereafter operating the punch to perform the punching operation.
7. In a bottom sealing machine for sealing the bottom flaps of cartons, in combination, movable carton holding means for operatively supporting a carton during the bottom flap folding and sealing operations, means for operatively supporting said carton holding means, connections between said supporting means and said holding means adapted to permit lateral movement of the latter with relation to said supporting means, and means for forming an opening in the bottom of the carton while held by said carton holding means, after the said bottom flap folding and sealing operations have been performed.
8. In a bottom sealing machine for sealing the bottom flaps of cartons, in combination, movable carton holding means for operatively supporting a carton during the bottom flap folding and sealing operations, means for operatively supporting said carton holding means, connections between said supporting means and said holding means adapted to permit lateral movement of the latter with relation to said supporting means, a die mounted on the carton holding means, a punch adapted to cooperate with the die to form an opening in the bottom of the carton while held by said carton holding means after the said bottom flap folding and sealing operations have been performed, and means for aligning the die with the punch prior to the operation of the latter, said aligning means being capable of effecting movement of said carton holding means with relation to its supporting means.
9. In a bottom sealing machine for sealing the bottom flaps of cartons, in combination, a forming block provided with a die in the bottom thereof, means for operatively supporting said forming block, connections between said supporting means and said block adapted to permit the block to be moved laterally with relation to said supporting means, a punch member adapted for cooperation with the die to form an opening in the bottom of the carton, and means for moving said block with relation to said supporting member whereby to effect alignment of the die and the punch including a registering member carried by said block and a second registering member adapted to cooperate with the registering member upon the block prior to the punching operation, and means for thereafter operating the punch to perform the punching operation.

STANLEY R. HOWARD.
